UNITED STATES PATENT OFFICE.

JOHN ROGER OLIVER, OF MEDFIELD, MASSACHUSETTS, ASSIGNOR TO REECE SHOE MACHINERY COMPANY, OF BOSTON, MASSACHUSETTS, A CORPORATION OF MAINE.

SEWING MACHINE.

Application filed April 8, 1925. Serial No. 21,544.

This invention relates to sewing machines, and more especially a shoe sewing machine of the class known as a welt-and-turn machine, in which the shoe insole is stitched to 5 the shoe upper lip and to the welt strip, although the novel features are applicable to other machines for stitching welts or strips to various materials.

The general object of the present invention 10 is to improve the operation of such sewing machines and especially to improve the mode of feeding, guiding and applying the welt strip. The usual means for guiding the welt strip to the work is what is known as the 15 "back gage," an example of which is shown in my prior application 712,035, filed May 9, 1924, this instrument comprising a long shank or bar slideable forwardly and rearwardly toward and from the work and carrying at its 20 front end a guide means in the nature of a loop through which the welt passes and which is regularly vibrated during the stitching, as to give the well known cycle of operations. This plan of controlling the welt presents a 25 number of practical difficulties, including the fact that the welt is not manipulated to the best advantage, and is not laid smoothly and accurately against the surface of the shoe or other work to which it is to be attached. 30 A further object of the present invention is therefore to overcome the well known drawbacks and objections presented by the welt manipulating devices as heretofore known. Other and further objects and advantages of 35 the present invention will be pointed out in the hereinafter following description of one form or embodiment of the invention, or will be apparent to those skilled in the subject.

To the attainment of the aforesaid objects 40 and advantages the present invention consists in the novel sewing machine, and welt handling mechanism, and the several novel features of combination, arrangement, operation, construction and detail as herein illustrated or described.

In the accompanying drawings Fig. 1 is a 45 right hand elevation of a sufficient portion of a shoe sewing machine to illustrate the principles of the present invention.

Fig. 2 is a rear elevation partly in section 50 on the line 2—2 of Fig. 1.

Fig. 3 is a front elevation of certain of the 55 parts of the mechanism including the welt conduit or grooved block constituting one of the characteristic features of the invention.

Fig. 4 is a right elevation in part similar to Fig. 1, but with the mechanism in a different position, and with the shoe and its relation to the mechanisms indicated.

Fig. 5 is substantially a left end view of the 60 welt conduit of the other figures.

Fig. 6 is a plan view of the welt conduit from above.

Fig. 7 is a right end view of the same.

Fig. 8 is a bottom view of the same. 65

Fig. 9 is a slanting view taken partly in section on the line 9—9 of Fig. 5.

Fig. 10 is a section taken on the slanting line 10—10 of Fig. 4 or 5, and showing the relation of the welt conduit member to the 70 welt and the work; the thickness of plate 43 and other small dimensions being somewhat exaggerated for clearness of illustration.

Referring to the drawings, some of the well known stitching instruments of welt 75 sewing machines are shown. Thus the work rest or bumper A is an instrument against which the work may be held during the stitching, giving support against rearward movement during the extraction of the needle, this 80 member having a sliding shank a which is intermittently locked forward and permitted to yield rearwardly in each stitch cycle. A channel guide B is indicated, this entering the channel in the shoe sole and thus giving 85 guidance to the progressing shoe. The needle C is barbed, and preferably of the curved type, arranged to enter and penetrate the welt strip w, the shoe upper y, and the sole lip x, from the rear side, and to retract bearing 90 a loop of thread supplied to the needle by the usual looper, not herein shown.

The machine frame may comprise a tall post, the upper end 10 of which is shown, and above this are various frame parts, including 95 two upright walls, the left hand wall 11 and the right hand wall 12, which afford bearings for the operating shaft 13, and between which is accommodated most of the operating mechanism. The shaft may be formed with 100 cranks to perform certain movements and cams for other movements. An outside cam disk 14 is shown and an inside cam disk 15, being respectively at the left and right hand sides of the left wall 11.

The work rest A, as stated, is supported on a shank a which is arranged to slide forwardly and rearwardly in suitable slideways in the left wall 11. The spring 17 is arranged to pull forwardly on the shank and work rest, 110

while a lock member 18 grips or binds the shank forwardly at certain parts of the cycle. The lock or grip arm 18 is fulcrumed at 19, and when swung into contact with the shank 5 *a* prevents rearward movement thereof. This type of work rest lock means is not herein claimed per se as it is shown and made the subject of claim in my copending application, already mentioned.

10 The connections for actuating the bumper lock member are utilized in part also for effecting the locking and releasing of the welt conduit member to be described, and for convenience so much of the connections as pertain to the bumper lock member will now be described. The inside cam disk 15, on the operating shaft 13, is provided with a peripheral cam 20, which cooperates with a follower 21 on a cam lever 22 located slantingly at the 15 rear of the shaft. A spring 23 presses on the cam lever to hold the follower to the cam. The lever has a hub 24 pinned to a rock shaft 25 arranged parallel to the main shaft at the rear part of the machine. At another point 20 on the shaft 25 it is provided with a downwardly extending rock arm 27, to the lower end of which is pivoted a link 28 extending forwardly and pivoted to the upper end of a guide arm 29, formed in one piece with a forward arm 30, the two fulcrumed at 31 to a fixed part. By these connections the link 28 is oscillated forwardly and rearwardly in synchronism with the other movements of the machine. At an intermediate point on the 25 link 28 is pivoted a link 32 extending downwardly and rearwardly to the lower end of the bumper grip arm 18. These several parts are so calculated that the grip arm will be 30 swung rearwardly into contact with the shank *a*, so as to lock the bumper forward while the needle is being retracted from the work.

35 The needle actuating lever 35 is indicated in Fig. 2, but for convenience elsewhere omitted as not directly involved in the present invention. The details however are fully shown in a copending application Serial No. 25,753, filed April 25, 1925, to which reference may be had. Fig. 2 merely shows that the 40 hub of the needle lever 35 is formed with a vertical slot 36 engaging a block 37 turning loosely on the countershaft or axle 25, for the purpose of enabling the effective center of the needle lever to be shifted during stopping for purposes described in the copending application.

45 The welt guiding and applying means of this invention comprises what I term a welt conduit 40, in the nature of a tube, or rather 50 an elongated block formed with a longitudinal groove, tunnel or passageway of substantial length, through which the welt strip may 55 pass freely from a source of supply and in a definite manner, the conduit member designed and arranged so that the welt strip issuing

from its end near the stitching point is laid smoothly and tangentially directly against the shoe or work to which the strip is to be attached. The welt conduit member is shown in exterior front view in Fig. 3, and in right 70 elevation in Figs. 1 and 4, while Figs. 5 and 7 show longitudinal end views from the left and right and Figs. 6 and 8 face views from the top and bottom, Figs. 9 and 10 being sections on the planes 9-9 and 10-10 of Fig. 5. 75 The block is shown as having a very irregular conformation for various purposes, including its mounting, and the need of clearing certain other parts of the machine, but the precise configuration is not essential so long as the 80 described principles of construction and operation are employed. From the stitching point the conduit member is preferably arranged to incline both upwardly and rearwardly to the right. A groove extending 85 through the member from end to end issues at the left end in substantial alignment with the surface of the leather or material to which the welt is to be attached, so that the welt is applied very smoothly and evenly, 90 in direct contact with the shoe, so as to minimize the likelihood of relative displacement during the applying of stitches. The groove through the conduit member is indicated by showing its right extremity or entrance 41, 95 see Figs. 3, 7 and 9, and its left extremity or exit 42, see Figs. 5, 6 and 9. The tunnel or groove is preferably made somewhat larger than the average welt or strip both in width and thickness. A gib 44 is shown within the 100 groove, pivotally secured at its right end, and adjustable inwardly by a screw 45, to effectively reduce the width of the groove to suit narrow welts. A second gib 46 is shown 105 pivoted near the exit end of the groove and similarly adjustable by a screw 47 to reduce the thickness of the groove to accommodate it to thin welts. Near the extreme left end 110 of the conduit member is shown a notch 48 to accommodate the needle as it oscillates forwardly and rearwardly. The lower part of the conduit member is provided with a rearward extension 49, having at its underside ratchet teeth 50 cooperating in the locking 115 forward of the member at certain points of time. The conduit member at its lower side has also a perforated lug 52 for connection to a link to be described. Extending downwardly through the body of the conduit member is a slot 54, by which the member is placed 120 in position upon a swinging carrier to be described. Within the slot 54 is a gib 55 upon which pressure may be applied by an exterior screw or bolt 56 so as to clamp the conduit member firmly to the carrier.

125 It will be perceived, especially by reference to Fig. 10, that the welt tunnel 41 is close to the lower forward side of the conduit member, so that only a thin wall 43 stands between the welt and the parts of the shoe to which it is 130

to be attached. Also, the left end of this wall 43 is abbreviated or terminated short of the stitching point, indicated by the needle position in Fig. 10, and the left end of the wall is 5 arranged and shaped, as shown, so as to facilitate the smooth application, in a substantially tangential direction, of the welt to the shoe, as well illustrated in Fig. 10. The 10 groove, with its gibs, accurately guides the welt strip, which travels smoothly and requires no feeding other than that afforded by the feed of the work, the welt strip thereby being laid flatly and accurately against the work at or in advance of the stitching point, so 15 that the attachment of the welt is effected to the best advantage.

While the welt conduit hereof might be employed in different ways, and mounted stationarily or for movement in different ways, 20 my preferred embodiment involves the following features. The conduit member is so mounted as to be movable toward the work in a swinging manner, preferably about an axis parallel to the feed direction located above 25 the conduit member, although the member might in some cases be pivoted at one end and swung at the other end. Another preferable feature is that the conduit member is not required to be periodically retracted from 30 the work, as was done with the old welt gage, but is preferably pressed or held forward to the work through all parts of the stitch cycle. As will be described resilient pressure is used, 35 preferably combined with means for changing the degree of pressure, the pressure being light while the conduit member adjusts itself to the position of the work, and being substantially increased before the retraction of the needle after penetration of the work, supplemented by positive locking means holding 40 the conduit member forward to the work during needle retraction. Certain of these features of novelty could be employed in connection with welt guides other than the conduit 45 member hereof, and claim is made thereto irrespective of the type of welt guide. The intercombination however of the described conduit member and the means of control thereof is found to give superior results in 50 accuracy, efficiency and convenience.

In order to allow for the swinging movement of the conduit member 40 it may be detachably mounted on a carrier, which is shown as comprising a bar 59 extending 55 downwardly into the slot 54 in the conduit member, and a yoke 60 extending upwardly and having hubs 61 fulcrumed on an axle 62, shown extending substantially parallel to the direction of feed of the work. The axle 62 60 is mounted at its right end in the side wall 12 and at its left end in a special bracket 64 secured to the left wall 11, the bracket shaped to give clearance of certain parts of the stitching mechanism.

65 It will be understood that the welt conduit

40 normally stands forwardly in contact with the work, but when no work is in the machine it is desirable to have the member come forward to a stop, and a fixed stop arm 65 is shown, secured to the bracket 64, the lower 70 end of the arm provided with an offset through which extends a set screw 66, adapted to be contacted by the yoke 60, thus adjustably positioning the conduit member when there is no work in the machine. 75

The work rest or bumper A is locked forwardly, as described, during the retraction of the needle, to resist the pull of the needle and thread upon the work, and it is desirable similarly to lock forward the conduit member 80 40 at the same parts of the stitch cycle. The toothed rack 50 at the underside of the conduit member is used for this purpose and a dog or pawl 68 is arranged to cooperate therewith. Fig. 1 shows the conduit member 85 standing forwardly, with no work in the machine, but Fig. 4 shows the machine in operation, and the dog 68 engaged with the rack 50. The dog is mounted on an arm 69 having a rear extension 70, the bell crank thus formed 90 being fulcrumed at 71. It will be noticed that the effective length of the arm 69, from the fulcrum 71 to the dog 68, is substantially tangential to the swinging movement of the rack 50, so that the fulcrum takes the brunt 95 of the pressure, giving a very rigid locking effect.

In order to operate the dog 68 at certain points in the stitch cycle a link 72 is shown 100 extending from the bell crank arm 70 to the bell crank arm 30 already mentioned, connected with the cam mechanism employed to control the locking means of grip arm 18 for the work rest A. By these connections the cam 20 operates not only the work rest lock 105 18, but the conduit member locking dog 68, in a manner which will be clear from the connections. When the link 28 is oscillated forwardly this swings the grip arm 18 away from the work rest and swings the dog 68 110 away from the rack, the two actions being preferably simultaneous. When the follower 21 passes off the enlarged part of the cam 20 the connections operate to apply both lock members, this position being indicated in Fig. 115 4, the other position in Fig. 1. It is desirable that the conduit member shall be capable of moving forwardly into closer contact with the work after the dog 68 has moved into locking position. For this purpose the link 120 72 may be constructed as follows, to introduce a resilient element. The rear end of the link 72 is formed with a spherical head 73, and the forward end of the arm 30 is provided with a spherical socket 74 engaging the head 73. A spring 75 surrounds the link 72, pressing the head and socket strongly together. Lock nuts 76 permit adjustment of the length of the link so as to adapt the dog 125 accurately to the rack. Normally the down- 130

ward swing of the arm 30 merely pulls the link 72 and thereby swings the dog downwardly. However, when the parts are in locked position, as in Fig. 4, the conduit member and rack 50 may be moved forwardly, the spring 75 permitting the dog 68 to yield sufficiently for this purpose.

Preferably the conduit member 40 is pressed forwardly against the work, or 10 against the stop 65, continuously, by resilient means, for example in accordance with the illustration. Attached to the lug 52 at the lower rear side of the conduit member is a long link 78, bent to clear certain parts and 15 near its rear end passing through a slide block 79, which is swivelled as will be described. A spring 80 surrounding the link is confined between the swivel block 79 and a pair of stop nuts 81 on the link, so that the spring is pressing forwardly, and forces the conduit member 20 yielding toward the stop 65. A second coil spring 82 surrounds the rear part of the link, between the block 79 and stop nuts 83. Fig. 1 shows these parts in normal position, 25 the spring 80 effecting forward pressure on the conduit member. Fig. 4 shows a change of adjustment wherein the spring 80 is highly compressed giving heavy forward pressure upon the conduit member against the work. 30 This change of pressure may be effected automatically by the following connections. The guide block 79 for the link 78 is shown swivelled near the lower end of a rock lever 35 which is fulcrumed on the shaft 25 as an axle. The arm 85 has an upward extension in the form of an arch 86 extending to the right, as seen in Fig. 2, and united with a sleeve 87, which extends through the left wall 11 of the machine frame. Exterior to the 40 wall is sleeve 87, surrounded by a collar 88, adjustable on the sleeve, the collar rigidly carrying a rock arm 89 which extends upwardly and at its extremity is pivotally connected with a link 90, which in turn extends 45 forwardly and is pivotally connected with the upper end of a bell crank arm 91, the other arm 92 of which extends forwardly and carries a follower 93 engaging a cam groove 94 in the face of the cam disk 14.

50 While the welt conduit rests in contact with the work, and preferably while the needle is advancing through the work, the cam 94 operates through the described connections to throw heavy pressure on the welt conduit, 55 thus forcing it strongly against the work, to bring it to the most advantageous position, where the dog and rack hold it locked until after the complete retraction of the needle. The rear spring 82 is under light or no compression, but serves to prevent loose movement or rattling, and serves as a cushion.

60 The general operation of the machine will be understood to those skilled in the subject of welt stitching. Fig. 1 shows the position 65 with the needle retracted fully, the same as it

would be in final stopped position. When the machine is stitching, and about the time the needle arrives at full retracted position the welt conduit is restored to a condition of light pressure, so that the work may be fed 70 without injury, the lock dog is retracted from the ratchet, and the bumper or work rest is rendered free; so that the work can readily adjust itself, as it is fed, and these instruments readjust themselves to the work. As 75 the needle starts forwardly toward the work the work rest lock and the welt conduit lock are rendered effective by the cams. About the time the needle reaches and penetrates the work the resilient pressing means is readjusted to produce the extra powerful pressure upon the conduit, so that it takes a position as far forward as possible. When the needle retracts the work is securely held by the work rest and welt conduit. The cooperative 80 action of the rest of the machine will be understood.

The described mechanism may be supplemented in various ways, for example by the addition of welt severing means operating 85 after completion of one shoe, welt end positioning means, arranged to hold the loose extremity of the advanced welt in proper position for starting a new seam, or an auxiliary feed means tending to thrust the welt through 90 its conduit toward the stitching point.

95 It will thus be seen that I have described a welt sewing machine embodying the principles and attaining the advantages of the present invention. Since many matters of combination, arrangement, design and detail may be variously modified without departing 100 from the principles of the invention, it is not intended to limit the invention to such matters except to the extent specified in the appended claims.

105 What is claimed is:

1. In a welt sewing machine, means for guiding the work along the direction of feed, means for stitching the welt to the work, comprising a needle operated to penetrate the work, and a welt applying device, comprising an elongated conduit member arranged longitudinally of the feed of the work and formed with an extended tunnel guiding the 110 advancing welt and applying it smoothly and directly to the work near the stitching point, said welt conduit member being adaptively movable, and having resilient means pressing it lightly to the work during feeding, and 115 heavily during needle operation.

120 2. In a welt sewing machine, means for guiding the work along the direction of feed, means for stitching the welt to the work, comprising a needle operated to penetrate at the 125 welt side of the work, a welt guide member, arranged at the same side of the work with the needle, and adaptively movable, a work rest also adaptively movable, and means normally maintaining the welt guide and work 130

rest in continuous contact against the work throughout the stitching, in all stages of each stitch cycle.

3. In a welt sewing machine, means for 5 guiding the work along the direction of feed, means for stitching the welt to the work, comprising a needle operated to penetrate at the welt side of the work, and a welt applying device, arranged at the same side of the work 10 with the needle, adapted to lay the welt smoothly tangentially upon the work, and means normally holding the welt applying device to the work continuously through all 15 parts of the stitch cycle comprising resilient pressure means and automatic connections for increasing and decreasing the pressure in timed relation to the stitch formation without retracting the device from the work.
4. In a welt sewing machine, means for 20 guiding the work along the direction of feed, means for stitching the welt to the work, comprising a needle operated to penetrate at the welt side of the work, and a welt applying device, arranged at the same side of the work 25 with the needle, adapted to lay the welt smoothly tangentially upon the work, and means normally holding the welt applying device to the work continuously through all 30 parts of the stitch cycle comprising resilient pressure means and automatic connections for increasing and decreasing the pressure in timed relation to the stitch formation without retracting the device from the work, and other means for locking the device to the 35 work during needle retraction.

5. In a welt sewing machine, means for 40 guiding the work along the direction of feed, means for stitching the welt to the work, comprising a needle operated to penetrate the work, a welt applying device arranged to be always free to move to the work, with resilient pressure means holding said device to the work, consisting of a stressed spring normally under light pressure, and means automatically increasing the stress and pressure of the spring periodically in timed relation to the needle operation.

6. In a welt sewing machine, means for 45 guiding the work along the direction of feed, means for stitching the welt to the work, comprising a needle operated to penetrate at the welt side of the work, and a welt applying device, arranged at the same side of the work with the needle, comprising a conduit

member arranged longitudinally of the feed 55 of the work and formed with a welt guiding slot to engage and steadily guide an extended length of the advancing welt in its approach toward the stitching point and apply it tangentially against the work near the stitching 60 point, said welt conduit member being fitted to swing toward the work, with a dog and tooth lock device to lock it to the work, one part of said device connected to the member and the second part fitted to swing into and 65 out of engaging position, said second part when in engaging position being substantially tangent to the swing of the member, cam connections for swinging the second part of the lock device, and a yielding element in said 70 cam connections.

7. In a shoe sewing machine of the class for stitching welts to shoes, means for guiding the shoe along the direction of feed, means for stitching the welt to the shoe, comprising a 75 curved barbed needle operated to enter at the welt side of the shoe, and a welt applying device, arranged at the same side of the work with the needle, comprising a welt guide member guiding the advancing welt and applying it smoothly and directly to the shoe near the stitching point, the said guide member being adaptively movable, and control means operating normally throughout the stitching to maintain the welt guide member 80 in continuous contact upon the shoe, namely, resistingly during the stitch formation and yieldingly during the feed in each cycle.

8. In a shoe sewing machine of the class for stitching welts to shoes, means for guiding a 90 shoe along the direction of feed, a curved needle operated to enter and penetrate at the welt side of the shoe, and adapted to receive thread at the opposite side of the shoe, and welt applying means comprising a welt guide 95 member, and control mechanism therefor operating to maintain the welt guide member in continuous contact with the shoe throughout the stitching of a seam by resilient forward pressure during a part of each stitch 100 cycle including the shoe feeding period and resistingly during the remainder of each stitch cycle including the needle retracting period.

In testimony whereof, I have affixed my 105 signature hereto.

JOHN ROGER OLIVER.
